UNITED STATES PATENT OFFICE.

WALTER R. LOCKHART, OF HOTCHKISS, COLORADO.

DESIGN FOR A GAME-BOARD.

43,764.

Specification for Design.

Patented Apr. 1, 1913.

Application filed October 11, 1912. Serial No. 725,818. Term of patent 14 years.

To all whom it may concern:

Be it known that I, WALTER R. LOCKHART, a citizen of the United States, residing at Hotchkiss, in the county of Delta and State of Colorado, have invented a new, original, and ornamental Design for a Game-Board, of which the following is a specification, reference being had to the accompanying drawing, forming part thereof.

The figure is a plan view of a game board showing my new design.

I claim:

The ornamental design for a game board, as shown.

In testimony whereof, I affix my signature, in presence of two witnesses.

WALTER R. LOCKHART.

Witnesses:

RAY DOUGHTY,
MAUDE DUKE.
